UNITED STATES PATENT OFFICE.

ELLIS J. WOOLF, OF MINNEAPOLIS, MINNESOTA, ASSIGNOR TO THE WOOLF VALVE GEAR COMPANY, OF SAME PLACE.

AIR AND GAS ENGINE.

SPECIFICATION forming part of Letters Patent No. 627,220, dated June 20, 1899.

Application filed September 19, 1898. Serial No. 691,332. (No model.)

To all whom it may concern:

Be it known that I, ELLIS J. WOOLF, a citizen of the United States, residing at Minneapolis, in the county of Hennepin and State 5 of Minnesota, have invented certain new and useful Improvements in Air and Gas Engines; and I do hereby declare the following to be a full, clear, and exact description of the invention, such as will enable others skilled in the 10 art to which it appertains to make and use the same.

My invention relates to air and gas engines, and has for its object to improve the construction with a view of increased efficiency.

15 To this end my invention consists of the novel devices and combinations of devices hereinafter described, and defined in the claims.

The invention is illustrated in the accompanying drawings, wherein like notations refer to like parts throughout the several views.

Figure 1 is a perspective view illustrating a compound engine embodying the preferred form of my invention. Fig. 2 is a vertical 25 cross-section of the same substantially on the line $x^2 x^2$ of Fig. 3. Fig. 3 is a vertical section lengthwise of the crank-shaft or substantially on the line $x^3 x^3$ of Fig. 2. Fig. 4 is a 30 sectional elevation in a plane lengthwise of the crank-shaft or substantially in the same plane as Fig. 3, illustrating the compound engine equipped with a modified form of my improvement; and Fig. 5 is a detail showing a face view of the valve-gear cam detached.

35 The numerals 1, 2, and 3 represent flange-castings which are set one on top of the other in the order named and are bolted or otherwise rigidly secured together. The said castings 1, 2, and 3 coöperate to form the base and the 40 cylinder castings of the engine. The casting 3 is shown as having rigidly secured thereto a casting 4, which serves as a cross-head guide, as will later more fully appear. The casting 3 is provided at its lower end with a head 5, 45 which serves as the partition or division-head between the high-pressure cylinder 6 and the low-pressure cylinder 8 and which head 5 is recessed to afford the explosion-chamber 7. The casting 2 and the head 5 in the casting 3 50 are formed with hollow walls, which coöperate to afford a water-jacket 9, surrounding a por-

tion of the high-pressure cylinder 6 and of the explosion-chamber 7. The water is kept circulating through the jacket 9 by any suitable connections. (Not shown.)

55 In the high and low pressure cylinders 6 and 8 are located corresponding high and low pressure pistons 10 and 12 on a common rod 11. To the low-pressure piston 12 is secured a cross-head 13, which works in the casting 4 60 - as a guide. The cross-head 13 is connected by a rod 14 to the crank-disk 15 on the crank-shaft 16. The castings 1 and 2 are so formed as to afford a bearing for said crank-shaft 16. The crank-disk 15 is shown located at one end 65 of the shaft 16, and the opposite end of the shaft 16 is provided with a suitable fly-wheel 17, which also may be used as the pulley for transmitting the power to any point desired. On the shaft 16, adjacent to the fly-wheel 17, 70 is mounted a cam 18, which operates on one arm of a rocker 19, which is pivoted to the casting 2, with its arms extending approximately in the vertical plane. This cam 18 and rocker 19 constitute the valve-gear for controlling the distribution-valves in a manner which will later be described. The end of the shaft 16 adjacent to the fly-wheel 17 is reduced, as shown at 16^a. On the same is loosely mounted a shipper or reversing sleeve 20, 75 which has attached to its inner end a key 21. The valve-gear cam 18 is loose on the shaft 16, but may be made fast thereto for rotation therewith by the key 21. For this purpose the cam 18 is provided on its face with a pair 80 of key-seats 22 at the opposite ends of an incomplete or segmental groove 23, countersunk in the hub of the cam. The shipper or reversing sleeve 20 is recessed to receive a spring 24, which reacts between the base of 85 the recess of said sleeve and the reduced end 16^a of the shaft, to which the outer end of the spring is made fast in any suitable way. The spring 24, reacting against the shaft 16 as a base of resistance, tends to hold the sleeve 90 20 and the key 21 in their innermost positions; but when it is desired to reverse the engine the said sleeve 20 and key 21 can be drawn outward, thereby permitting the shaft 95 to revolve, while the cam 18 remains stationary until the inner end of the key 21 passes from one end of the groove 23 to the other, 100

thereby finding entrance to the opposite member of the two key-seats 22. Just how this reverses the engine will appear later when tracing the operation.

5 The high-pressure piston 10 and the rod 11 are recessed or formed hollow for coöperation to afford a mixing-chamber 25 for the air and gas. As shown, a gasoline-tank 26 is secured to the casting 4, and from the same a valve-
10 pipe 27 depends into the bore of the hollow rod 11. Said supply-pipe 27 is shown as provided with a hand-valve 28. As shown, the said pipe 27 has formed integral therewith a solid extension 27^a at its lower end, and at
15 the junction of the hollow and solid sections the pipe-section 27 is provided with small perforations *b* for the outlet of the gasoline. With this construction the solid section 27^a serves as a distributor for the gasoline. The
20 parts 27 and 27^a are of course of small diameter compared to the bore of the hollow rod 11, and this rod being open at its upper end affords an abundance of clearance or space
25 for the entrance of air. The said hollow piston 10 is provided with a valve 29, controlling a port opening to the compression end of the high-pressure cylinder. The said valve 29 is shown as provided with a light spring 30 sufficient to overcome the gravity of the valve for
30 holding the same to its seat.

The base-casting 1 is formed hollow to afford a storage-chamber 31. This storage-chamber 31 is provided with valve-controlled ports opening to the opposite ends of the high-pressure cylinder 6. As shown, the casting 2 is provided with a recess 33, which is always in communication with the recess 31 in the base-casting 1 through a suitable passage 32 connecting the same. A port *c* leads from the
35 compression end of the high-pressure cylinder 6 to the valve-chest 33 and is under the control of a gravity-valve 34, as shown in Fig. 2. The upper end of the chest 33 is provided with a port *d*, opening to the explosion-chamber 7 and, under the control of a valve 35. The valve 35 is provided with a downwardly-extended guide-stem 36, which carries at its lower end as a nut an angular bracket 37. A spring 38 reacts against said bracket 37
40 and one wall of the chest 33 for holding the valve 35 to its seat against the pressure from the storage-chamber 31. A hand-shaft 39 extends into the chest 33 through the chest-plug 41 and is provided on its inner end with
45 an eccentric 40, which may be brought into action on the bracket 37. The said parts 39 and 40 constitute a hand device by which the valve 35 may be held in its open position for admitting storage-pressure to the cylinders
50 when desired for starting the engine, as will later more fully appear.

The valve 35 has a flanged head 42, which overreaches the upper end of the piston 10 for causing the piston 10 to raise the valve
55 35 into its open position at the limit of said piston's upward stroke. The said valve 35 also serves as one member of the electrodes

for the electric igniter. The other member 43 is fixed to and insulated from the upper end of the piston 10 at a part of the same 70 underlying the flange 42 on the valve 35. This insulated electrode 43 is provided with an insulated wire 44, leading to one pole of a suitable battery or other source. The valve 35 and the engine-castings are connected with 75 the other pole of the battery or source by suitable connections, which in the present instance include a circuit maker and breaker subject to the action of the reversing device for opening the igniter-circuit independent 80 of the electrodes when the engine is reversed. For this purpose, as shown, the wire 48 from the battery to the engine-castings is attached or seated in an insulating-ring 45, carried on the shipper-sleeve 20. The insulating-ring 85 45 is loose on the sleeve 20 and has a pin 46 engaging a groove 47 in said sleeve. The wire 48 is seated in the inner profile face of said ring 45 and is normally held in contact with the hub of the fly-wheel 17 under the action of the spring 24; but when the shipper-sleeve 20 is pulled outward, as required for reversing the engine, the insulating-ring 45 and the wire 48 will be carried with it, thereby opening the circuit between the wire 48 90 and the fly-wheel 17. The purpose of this will more fully appear in tracing the operation of the engine. The wire 48 would be held, of course, in practice in any suitable way to prevent the sleeve or ring 45 from 100 turning with the crank-shaft.

A port *f* leads from the explosion-chamber 7 to the port *f'*, which leads to the low-pressure cylinder 8. The port *f* is under the control of a valve 49, which opens inward. The 105 port or passage *f'* is tapped by a final exhaust-port *f''*, leading to a valve-chest 51, tapped by the final exhaust-pipe 52. The final exhaust-port *f''* is controlled by a valve 50, which opens outward. The said valves 49 and 50 110 are in line with each other and open in opposite directions against a common retraction-spring 53. As shown, the valve 50 is recessed and the spring 53 encircles the stem of the valve 49 between the base of the recess in the valve 50 and a head 54 on the 115 stem of the valve 49. The spring 53 therefore serves to seat both valves. This spring 53 must be of sufficient tension to resist the pressure from the low-pressure cylinder 8. The valve 50 is slotted to receive the upper end of the upper arm of the rocker 19, forming a part of the valve-gear. The rocker-arm entering the valve 50 works between the head 54 on the valve 49 and the outer head of the 120 valve 50, opening said valves alternately in opposite directions, at the opposite limits of the rocker's throw, under the control of the cam-wheel 18.

Operation: Assume that the engine has been 130 started and that the storage-chamber 31 contains air and gas at working pressure. Then during the upstroke of the pistons 10 and 12 a charge will be drawn in from the mix-

ing-chamber 25 through the hollow rod 11 and delivered into the compression end of the high-pressure cylinder 6, the valve 29 opening for this purpose under the vacuum produced behind the piston 10. On the down-stroke of the pistons the said charge will be compressed within the compression end of the high-pressure cylinder 6 until it exceeds the pressure in the storage-chamber 31, and 5 when that point is reached the valve 34 will open, thereby permitting the charge to be forced into the storage-chamber 31 under the continued downward movement of the high-pressure piston 10. At the limit of said high-pressure piston's downward stroke the valve 34 closes by gravity, thereby holding the charge or confining the same within the storage-chamber 31. On the next upward movement of the pistons the charge being traced 15 is held confined under pressure in the storage-chamber 31 until the high-pressure piston 10 approaches the limit of its upward stroke, whereupon the said piston 10 acting on the flange 42 of the valve 35 will raise the same, thereby opening the port *d* from the storage into the explosion chamber 7 and admitting the charge thereto. Then when the pistons again start downward the valve 35 20 first closes under the action of the spring 38, and then the insulated electrode 43 on the piston separates from the flange 42 of the valve-electrode 35, thereby producing the spark and causing the explosion. The working stroke of the high-pressure piston then 25 takes place, and during the same the charge which had been drawn into the compression end of the high-pressure cylinder during the last previous upstroke of the piston is compressed into the storage-chamber in the same 30 way as the charge originally traced. Upon the completion of said high-pressure stroke the valve-gear will open the valve 49, thereby permitting the partly-spent gases to pass through the ports *f'f'* into the low-pressure cylinder 8. The low-pressure stroke then 35 takes place, and at its completion the valve-gear will open the final exhaust-valve 50, thereby permitting the final exhaust through the ports *f'f'* and *f²* into the chest 51 and out 40 through the exhaust-pipe 52. At this time the valves will all be in the positions illustrated in Figs. 2 and 3 of the drawings ready for another explosion.

In the foregoing statement a charge has 45 been traced from its entrance through the mixing-chamber 25 through all the subsequent steps of its storage and use to the point of final exhaust. In order to trace a single original charge in the manner above stated, 50 it was necessary to follow through more than one cycle of the engine actions. One high-pressure and one low-pressure stroke of course complete one cycle of the engine's action. Every stroke of the pistons is a working 55 stroke. At every low-pressure stroke a charge is drawn from the mixing-chamber 25 into the compression end of the high-pressure cyl-

inder 6, and at every high-pressure stroke this charge is compressed into the storage-chamber 31. The charge thus compressed 70 into the storage-chamber 31 under the working high-pressure stroke is held in said storage-chamber 31 under pressure during the following low-pressure stroke, and at the completion of the low-pressure stroke a charge is 75 admitted from the storage to the explosion chamber to be exploded for the next working high-pressure stroke.

From the foregoing statements it must be obvious that in this engine the compression 80 of the charge or unexploded gases takes place under the explosion or high-pressure stroke. This of course is a radical difference over the ordinary standard gas-engine, wherein the compression takes place under the momentum of the moving parts. Hence by properly 85 proportioning the parts of this engine the effective pressure on the crank may be kept substantially uniform under both the high and the low pressure strokes without regard 90 to the question of momentum in the moving parts. It follows that with this engine a small fly-wheel is sufficient. Otherwise than 95 for reversing, which will now be described, a fly-wheel would be no more needed than on a steam-engine.

The reversing action.—It has already been stated that to reverse the engine it is only necessary to pull the shipper-sleeve 20 into its outermost position, and that thereupon the cam-wheel 18 will stand stationary while the shaft continues to turn until the key 21 rides from one end to the other of the groove 23, so as to reengage the opposite member of the key-seats 22 in the cam-wheel 18. When 100 this shift has taken place, the parts will be properly related to make the valve actions come right after the engine has reversed. Directing attention now to the reversing action, let it be assumed that the engine was 105 in motion and the shift of the sleeve 20 took place when the parts were all in the positions shown in Figs. 2 and 3. The distribution-valves 49 and 50 would then remain in the 110 positions shown in said Figs. 2 and 3 while the pistons made their downstroke. Thereupon the distribution-valves 49 and 50 again 115 becoming subject to the valve-gear as set for reversing will open and close in the reverse order of time. In virtue of this change in 120 the timing the exhaust-valve 50 remains open during the next upstroke of the pistons under the momentum of the moving parts, and thereby permitting air to be drawn in through the ports *f²* and *f'* into the low-pressure cylinder 125 8. On the next downstroke of the pistons, continuing under the momentum of the moving parts, the final exhaust-valve 50 being closed and the valve 49, controlling the port *f*, being open, the air and gases in the explosion-chamber 7 and the low-pressure cylinder 8 will first equalize and then be compressed 130 into the high-pressure cylinder 6 on the explosion side of the high-pressure pis-

ton 10 and will there be held when the valve 49 closes. These same actions will be repeated until the air thus pumped into the two cylinders and compressed equals or exceeds the momentum of the moving parts. As quick as this occurs the engine will stop and reverse under the pressure thus accumulated in the two cylinders. The valve motions having been set to come right under 10 this reversed motion of the engine the engine will continue to run in the opposite direction under working pressures from explosions.

The reversing action of the engine herein disclosed, as above described, is identical 15 with the reversing action of the engine disclosed in my pending application, Serial No. 634,182, filed April 27, 1897, and allowed November 29, 1898, entitled "Air and gas engine," and in the said pending application, Serial No. 634,182, I have broadly claimed the construction whereby this result is accomplished as a pioneer invention.

The presence of a circuit maker and breaker operated by the reversing device for opening 20 the igniter-circuit independently of the igniter-electrodes, as hitherto described, is an important feature in relation to the reversing action of this engine. By that provision, whereby the circuit is opened, whenever the 25 shipper-sleeve 20 is thrown into its outermost position no further explosion can take place until said shipper-sleeve is released and the key 21 is reseated in the opposite member of the seats 22 at the opposite limit of the groove 23 in the cam-wheel 18. Explosion is thereby avoided until desired for the working stroke 30 in the reverse direction of the engine, and no explosion can take place back into the storage-chamber 31 under the action of the igniter-electrodes and the opening of the valve 35.

Starting.—In the foregoing description of the operation it was assumed that the engine had been started. From that description it must be obvious that whenever the engine 45 stops the storage-chamber 31 will contain air and gas under working pressure. Hence whenever it is desired to start the engine all that is necessary is to manipulate the hand device 39 and 40, thereby raising the valve 35 and admitting storage-pressure to the cylinders under the control of the distribution-valves 49 and 50. The parts are so proportioned that when the eccentric 40 of the hand device is in its highest position acting on the 50 bracket 37 the valve 35 will be raised to an extreme position, so as to afford clearance between the flange 42 thereof and the other member 43 of the igniter-electrode, so as to avoid explosion until after the engine has 55 started.

The modified construction illustrated in Fig. 4 differs from the construction shown in the other views and hitherto described in certain features, which will now be noted. In 60 this modification the high-pressure piston p , rod p' , low-pressure piston p^2 , and cross-head p^3 are all hollow and in communication with

each other for coöperation to form a storage-chamber p^4 . The high-pressure piston p is provided with a gravity-valve p^5 , controlling 70 a port p^6 , opening to the compression end of the high-pressure cylinder 6, and is also provided with a spring-seated valve p^7 , controlling a port p^8 , opening into the explosion-chamber 7. The stem of the valve p^7 projects through a guide-passage in the upper 75 wall of the piston p in position to strike the insulated member p^9 of the pair of igniter-electrodes, one of which is afforded by the valve p^7 . In this instance the fixed electrode 80 p^9 is secured to the upper wall of the explosion-chamber 7 and suitably insulated therefrom, as in the other form the valve p^7 receives current from the engine-casting. The charge is admitted to the compression end of 85 the high-pressure cylinder 6 through an inlet q from a mixer of the ordinary or any suitable kind, the position of which is shown in dotted lines only at q' in Fig. 4.

Having regard to the action, the material 90 difference is due to the location of the storage-chamber p^4 in the moving parts p p' p^2 p^3 instead of in a separate reservoir independent of the moving parts of the engine, as in the other form. In view of this difference 95 in the location of the storage-chamber the storage is not available in the construction shown for starting the engine. On account of its location it would be inconvenient to provide access to the storage-chamber with a 100 suitable hand device, such as would be required for starting purposes. The valve p^7 , controlling the port p^8 , is held to its seat by a spring p^{10} , which must be of sufficient tension to withstand the explosion-pressure 105 within the chamber 7 less the storage-pressure in the chamber p^4 .

Having regard to both forms, it will be convenient to distinguish the valves which control the inlet and outlet ports to and from the 110 storage-chamber as the "charging-valves" for convenience of comparison with the distribution-valves 49 and 50, which, of course, are subject to the valve-gear.

It will be understood that many of the 115 details might be changed and that the principal features of the invention are capable of considerable modification in construction and arrangement without departing from the principle of my invention.

What I claim, and desire to secure by Letters Patent of the United States, is as follows:

1. A gas-engine having a storage-chamber into which the charge is compressed during each explosion stroke of the piston, and is held under pressure during each exhaust stroke thereof, and from which said charge is admitted, under pressure, to the explosion-chamber at the completion of said exhaust stroke, in combination with suitable valve 125 mechanism for controlling said action, including an admission-valve to the explosion-chamber operated by the piston, substantially 130 as described.

2. In a gas-engine, the combination with a cylinder closed at both ends and a piston working therein, of a storage-chamber having ports to both ends of said cylinder, and valve mechanism controlling said ports, with all of said parts so arranged that the charge is compressed into said storage-chamber by the piston during the explosion stroke, is held therein under pressure during the exhaust stroke of the piston, and is admitted, under pressure, to the explosion-chamber, at the completion of said exhaust stroke, and which valve mechanism includes an admission-valve to the explosion-chamber operated by the piston, substantially as described.

3. In a gas-engine, the combination with a cylinder closed at both ends to form compression and explosion chambers at its opposite ends, of a hollow piston and rod serving as a mixing-chamber for the air and gas and provided with a valve-controlled port opening to the compression end of the cylinder, and a storage-chamber with valve-controlled ports to both ends of said cylinder, all for co-operation, substantially as described.

4. In a compound gas-engine, the combination with high and low pressure cylinders and pistons, of distribution-valves controlling the compounding and final exhaust ports, with

said distribution-valves mounted to seat opposite to each other and connected for opposite movements against a common retracting-spring, and a single valve-gear operating both of said valves, substantially as described.

5. In a compound gas-engine, the combination with the high and low pressure cylinders set tandem, the high-pressure cylinder being closed at both ends to form compression and explosion chambers at its opposite ends, of the high and low pressure pistons on a common rod, the high-pressure piston and the rod being hollow to afford a mixing-chamber for the air and gas, a valve-controlled port in said high-pressure piston, opening from its recess or mixing-chamber to the compression end of said high-pressure cylinder, a storage-chamber having valve-controlled ports leading to the opposite ends of said high-pressure cylinder, suitable distribution-valves and a valve-gear, all for co-operation substantially as described.

In testimony whereof I affix my signature in presence of two witnesses.

ELLIS J. WOOLF.
